(57) **CLAIM**

The ornamental design for a footwear, as shown and
described.

DESCRIPTION

The present application is related to U.S. Design patent
application Ser. No. 29/658,604, entitled Footwear Outsole
Or A Portion Thereof, U.S. Design patent application Ser.
No. 29/658,615, entitled Footwear Outsole Or A Portion
Thereof, and U.S. Design patent application Ser. No. 29/658,
621, entitled Footwear Outsole Or A Portion Thereof, all
filed concurrently herewith, the entire disclosures of which
are incorporated herein by reference.

FIG. 1 is a perspective view of the footwear according to my
design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines of even length show environment and
portions of the footwear that form no part of the claimed
design. Broken lines of uneven length define the bounds of
the claimed design, and also form no part thereof.
